US0D1111869S

(12) **United States Design Patent** (10) **Patent No.:** **US D1,111,869 S**
(45) **Date of Patent:** **** Feb. 10, 2026**

(54) **MEASURING WHEEL**

(71) Applicant: **Apex Brands, Inc.**, Apex, NC (US)

(72) Inventors: **Brian Butler**, Charlotte, NC (US);
Nicholas Ryan Imsand, Huntersville, NC (US)

(73) Assignee: **Apex Brands, Inc.**, Apex, NC (US)

(**) Term: **15 Years**

(21) Appl. No.: **29/939,368**

(22) Filed: **Apr. 26, 2024**

(51) LOC (15) Cl. **10-04**

(52) U.S. Cl.
USPC **D10/70**

(58) **Field of Classification Search**

USPC D10/65-67, 69-71, 73
CPC . G01B 21/02; G01B 5/14; G01B 5/02; G01B 3/12; G01B 7/32

(57) **CLAIM**

The ornamental design for a measuring wheel, as shown and described.

DESCRIPTION

FIG. 1 is a perspective view of a measuring wheel of the present invention;

FIG. 2 is a front view of the measuring wheel;

FIG. 3 is a back view of the measuring wheel;

FIG. 4 is a right side view of the measuring wheel;

FIG. 5 is a left side view of the measuring wheel;

FIG. 6 is a top view of the measuring wheel; and,

FIG. 7 is a bottom view of the measuring wheel.

The broken lines shown in the drawings illustrate portions of the measuring wheel that form no part of the claimed design.

1 Claim, 7 Drawing Sheets
